UNITED STATES PATENT OFFICE.

JOSEPH A. SCOTT, OF SHELBY, IOWA.

DESIGN FOR A GAME BOARD.

Application filed August 7, 1924. Serial No. 10,399. Term of patent 7 years.

To all whom it may concern:

Be it known that I, JOSEPH A. SCOTT, a citizen of the United States, residing at Shelby, county of Shelby, and State of Iowa, have invented a new, original, and ornamental Design for a Game Board, of which the following is a specification, reference being had to the accompanying drawing, forming a part thereof.

The figure is a plan view of the game board.

I claim:

The ornamental design for a game board, as shown.

JOSEPH A. SCOTT.
